REFRIGERATING APPARATUS

Martin J. Goulooze, Grand Rapids, Mich., assignor to Nash-Kelvinator Corporation, Detroit, Mich., a corporation of Maryland

Application November 9, 1940, Serial No. 365,138

2 Claims. (Cl. 220—9)

This invention relates to refrigerating apparatus and more particularly to refrigerator cabinet construction.

This application is a continuation in part of application filed November 9, 1940, Serial No. 365,138.

One of the objects of my invention is to provide an improved arrangement for securing a breaker strip to the metal walls of a refrigerator cabinet.

Another object of my invention is to provide an improved arrangement for forming a pocket for the aforesaid breaker strip around the front wall of the cabinet.

Further objects and advantages of the present invention will be apparent from the following description, reference being had to the accompanying drawings, wherein a preferred form of the present invention is clearly shown.

In the drawings:

Fig. 1 is a front view in elevation of a refrigerator cabinet embodying the invention;

Fig. 2 is a view taken along line 2—2 of Fig. 1;

Fig. 3 is a fragmentary side view in elevation of the liner or inner shell;

Fig. 4 is a perspective view of a clip;

Fig. 5 is a bottom plan view of the clip;

Fig. 6 is a side elevational view of the clip;

Fig. 7 is a fragmentary cross-sectional view of a corner of a cabinet and door embodying a modified form of the invention;

Fig. 8 is a fragmentary cross-sectional view taken along line 8—8 of Fig. 7;

Fig. 9 is a fragmentary cross-sectional view taken along line 9—9 of Fig. 8;

Fig. 10 is a fragmentary front elevational view of the cabinet of the modified form with parts broken away and parts shown in section;

Fig. 11 is a fragmentary cross-sectional view taken along line 11—11 of Fig. 10, and

Fig. 12 is a cross-sectional view of a further modified form of constructing the outer shell of the cabinet.

Shown in the drawings is a refrigerator cabinet 20 of the household type. The cabinet 20 comprises an inner metal casing, shell, or liner 22 within an outer metal casing, or shell 24 with the walls thereof in spaced relation for the interposition of heat insulation material 25 therebetween. The inner shell or liner 22 forms the walls of a food storage compartment 26. Access opening 27 is formed in the front wall to compartment 26 closed by a door 29.

The outer casing 24 is formed with an inwardly turned portion 30 extending peripherally to the

door opening and forms a portion of the front wall of the cabinet. The front wall portion 30 is formed with extended metal that extends reversely, as at 32, to form the front wall of double wall thickness together with a portion of the outer side wall, as at 33. The extended portion is turned from the side wall to form a section 34 in spaced parallel relation to the front wall 30. A pocket 35 is formed between section 34 and the front wall. The section 34 extends a short distance beyond the edge of the front wall.

The inner liner or casing 22 is formed with a lateral flange 37 extending peripherally adjacent the door opening 27. The marginal edge 39 of the flange is bent at right angles to extend rearwardly from the portion 37. The portion 37 is in planular alignment with the section 34 of the outer shell with their edges terminating in spaced apart relation.

A breaker strip 40 extends between the inner and outer casings. One edge of the breaker strip is confined within the pocket 35 and its opposite edge lies flush against the lateral flange 37. The breaker strip may be made of plastic, fibrous material, "Bakelite" or any non-hydroscopic, non-metallic material. Similar breaker strips are positioned along the other sides of the cabinet on the front wall adjacent the opening 27 thereof, and immediately above the food storage compartment at the top of the cabinet, and also immediately below the food storage compartment. Since the principle of attaching the breaker strips to the cabinet and the principle of attaching the other breaker strips are the same, there is only shown in detail the breaker strip 40 and the way it is attached.

In attaching the breaker strip it has been found that where the liner and lateral flange are coated with vitreous enamel that threading of screws therein caused chipping of the enamel. To eliminate this and provide for means of securing the breaker strip thereto, clips 41 are attached at spaced intervals or positions to the edge 39 of the lateral flange. The clips 41 are formed with a U-shaped section comprising sides 44 and 45 adapted to embrace opposite sides of the flange's edge 39. The side 44 is extended at right angles forming a locking section 47 which is pierced and the sides of the opening are flared to provide threadable engagement for the shank of screw 42. To center and locate the clips 41 along the edge 39 so as to be in alignment with a respective bored passage in the breaker strip for the reception of the screws 42, the edge 39 is formed with

a plurality of spaced slots 43. The side 45 of clip 41 is punched with a semi-circular opening with its edge flared inwardly, as at 49. The flared edge 49 is receivable in a respective slot 43. Thus each of the clips are definitely located by the engagement of edge 49 in slot 43 for threadably receiving a respective screw 42 in fastening the adjacent edge of the breaker strip to the lateral flange. In the drawing the slots 43 are shown elliptical, it will be obvious that they may be formed either square, round, oblong, or where desired instead of slots there may be a series of indentations into which the flared edge may be received for the purpose of centering the clips.

The opposite edge of the breaker strip is confined in pocket 35 and secured by screws 42 to the section 34. By this arrangement the breaker strip is securely attached to the inner and outer casing, while at the same time the inner casing or liner 22 is securely supported by the outer casing 24.

To conceal the screw heads and provide a protecting cover for the breaker strip I have provided a cover 50 which extends across the front face of the breaker strip. The cover 50 is formed of thin gauge metal, preferably .010 inches or less in thickness, and which has a low heat conductive value as stainless steel and the like. One edge of the cover member 50 is inserted in the pocket 35 to be frictionally held between the front wall and breaker strip. The opposite edge is bent to extend around the edge of the breaker strip and insertable between the lateral flange and breaker strip. The breaker strip is longitudinally grooved with an inclined side 51 against which frictionally engages the marginal edge 52 of the cover member. This arrangement permits a self locking of the cover over the breaker strip.

Any door of suitable construction may be used with the cabinet. As shown in the drawings, there is provided a door 29 having an outer metallic shell 54 and an inner panel 55. The inner panel 55 may be formed of plastic, fibrous or other low heat conducting material. Insulation 56 is interpositioned between the shell and panel.

Secured to the door is a gasket 58 that extends peripherally about the perimeter of the door and adapted for engagement with the front wall of the cabinet forming a seal therewith so as to prevent air entering the food storage compartment. The gasket is secured by an integrally formed tongue 59 that is clamped between the shell and panel secured together by screws 60. The heads of screws 60 are concealed by the overlapping gasket 51.

In the modified arrangement shown in Figs. 7 to 11 the outer casing 90 is formed with a front wall section 92. The front wall is reinforced to a double wall thickness by welding thereto sheet metal member 94. The member 94 extends also a determinable length along in welded relation with the side wall of casing 90, and thence turned to extend in spaced parallel relation, as at 95, to the front wall. The section 95 terminating beyond the edge of the front wall to threadably receive screws in the affixing of the breaker strip 97. The opposite edge of the breaker strip is similarly secured by screws threadable into clips affixed to the inner liner 98 as described in the preferred form.

In some cases it has been found desirable to provide additional means to support the inner liner to the outer casing. To this end there are provided gusset supporting arrangements 100 in

each corner, which may, if desired, be also used with the already described preferred form shown in Figs. 1 and 2. The gusset arrangement comprises a gusset plate 102 secured by weld across the corner between side and top, or side and bottom section 95. Secured by weld, and the like, to the lateral flange of the liner is a plate 104 adapted to overlie the gusset plate and be secured thereto by screw 105. A spacer 107 of non-heat conducting material is interposed between the gusset plate and plate 104.

In the arranging of the breaker strip and its respective cover member around the sides, top and bottom adjacent the door opening there are formed gaps between the adjacent adjoining members. Closing this gap is a corner strip having a face portion 110 overlying the adjacent edges across the gap. Extending rearwardly from the face portion is a U-shaped section 112 adapted to embrace an edge of one of the breaker strips. In the attaching of the corner strip, it is slid longitudinally along the gap with one end entering the pocket, and the opposite end bent to form an angular corner 114 between the adjoining breaker strips. The corner strip is thus locked in position by the U-shaped portion engaging behind a breaker strip.

In Fig. 12 there is shown a further modified form of the invention whereby the pocket 35 is formed by welding a rib section 120 to the side wall of the outer casing 122 to extend parallel to the front wall 124 formed of single thickness.

While I have described the preferred forms of my invention, I do not wish to limit myself to the precise details as shown and described, but wish to avail myself of such variations and modifications as may come within the scope of the appended claims.

I claim:

1. A refrigerator cabinet construction comprising inner and outer metal shells having a door opening formed therein, said shells having edge portions about the periphery of the door opening, the metal of the edge portion of the outer shell being bent to form a pocket and including a section extending toward the inner shell, the metal of the inner shell being bent to provide a flange extending toward the outer shell but spaced therefrom and being arranged upon substantially the same plane, a short turned flange carried by said flange extending rearwardly from said door opening in substantially parallel relation with the side wall of said inner shell, and a breaker strip of substantially the same thickness as the width of said pocket secured to said shells, said breaker strip having a portion thereof extending into said pocket with its inner face in contact with said section, bracket means removably clamped about the edge of the turned flange and carried thereby, said bracket including a portion extending on substantially the same plane as said flange and said section, and means securing another portion of said breaker strip to said portion of the bracket and clamping said breaker strip with its face in contact with said flange.

2. A refrigerator cabinet construction comprising inner and outer metal shells having a door opening formed therein, said shells having edge portions about the periphery of the door opening, the metal of the edge portion of the outer shell being bent to form a pocket and including a section extending toward the inner shell, the metal of the inner shell being bent to provide a flange extending toward the outer shell but spaced

therefrom and being arranged upon substantially the same plane, a perforated short inturned flange carried by said flange extending rearwardly from said door opening in substantially parallel relation with the side wall of said inner shell, and a breaker strip of substantially the same thickness as the width of said pocket secured to said shells, said breaker strip having a portion thereof extending into said pocket with its inner face in contact with said section, bracket means extending around the edge of and on op-

posite sides of said inturned flange in parallel relationship therewith and having a tongue portion extending into said perforation for locking engagement with said flange, said bracket including a portion extending on substantially the same plane as said flange and said section, and means securing another portion of said breaker strip to said portion of the bracket and clamping said breaker strip with its face in contact with said flange.

MARTIN J. GOULOZZE.
